ANDREW HELDRICH, OF PHILADELPHIA, PENNSYLVANIA, ASSIGNOR TO LESKOLE AIR VALVE COMPANY, INC., OF NEW YORK, N. Y., A CORPORATION OF NEW YORK.

RADIATOR VENT VALVE.

1,403,162.

Specification of Letters Patent. Patented Jan. 10, 1923.

Application filed June 15, 1920. Serial No. 389,080.

To all whom it may concern:

Be it known that I, ANDREW HELDRICH, a citizen of the United States, and a resident of the city of Philadelphia, in the county of 5 Philadelphia and State of Pennsylvania, have invented certain new and useful Improvements in Radiator Vent Valves, of which the following is a specification, reference being had to the accompanying drawings.

10 My invention relates to valves for radiators for permitting the escape of relatively cold air or vapors and preventing the escape of the heating medium therefrom.

15 Among the objects of my invention is to provide a new and useful valve of the character aforesaid, which is sensitive and reliable in operation, will not require attention, or get out of order, and may be manufactured in large quantities at a relatively 20 low cost.

Another object of the invention is to provide a valve of the character aforesaid adapted to effectually release the relatively 25 cold air and vapors from the radiator but which will guard against the escape of the heating medium during the operation of the heating system, and which will operate to permit the inflow of air upon the draining 30 of the radiator when the heating system is thrown out of operation.

Other objects and advantages of my invention will appear more fully hereinafter.

Referring to the drawing, Fig. 1 is a vertical transverse section of a form of valve constructed in accordance with one embodiment of my invention, with the parts in one position of operation; Fig. 2 is a similar view showing the parts in another position of operation, and Fig. 3 is a fragmentary sectional view of a modified form of valve.

Referring more particularly to the drawing, wherein like reference characters designate corresponding parts in the several views, I have shown a valve comprising a connection 1 provided with screw threads 2 adapted to be communicably connected to a radiator at any suitable point. The connection 1 may be provided with a passage 3 leading into a well 4, open at its upper end and suitably threaded to receive a cup 5 provided in its bottom with a tapered valve seat 6 and having at its upper portion

a laterally extending annular flange 7 surrounded by an upwardly extending rim 8. Within the rim 8 may be positioned, in any suitable manner, as by frictional engagement, a shell 9 extending upwardly a suitable distance and provided with a closed upper end 10. The latter may be shaped to provide an annular concave portion 11, against the curved surface of which the fluids passing upwardly in the shell 9 may contact and be given a reflex flow, and a 65 preferably flat circular portion 12 provided with a vent perforation 13 and a central aperture 14, adapted to guide an end of a valve stem 15. The upper end of the shell 9 may be exteriorly reduced in diameter to 70 form an annular seat or shoulder 16 with which may frictionally engage the rim of a cap 17 whereby the outer surface of the cap 17 will form a continuation of the exterior surface of the shell 9. The cap 17 may be provided with a vent opening 18 at any suitable point as in the top thereof, and preferably in staggered relation to the vent perforation 13. Within the shell 9 and coaxial therewith, is disposed the valve stem 15 with 80 one end guided through the aperture 14 and the other passing through the port of the valve seat 6 into the well 4. The stem 15 may be provided near its lower end with a valve 19 of any suitable form, that shown 85 for illustration being conical, adapted to seat against the seat 6 in the lower portion of the cup 5. Intermediate the ends of the stem 15 may be rigidly connected in any suitable manner, a control member comprising a disk 20 and a bell shaped member 21 extending thereabove and closed at its upper end. The disk 20 is provided with an annular downwardly extending flange 22, the latter carrying adjacent its lower extremity an outwardly extending rim 23 disposed substantially parallel to the flange 7 of the cup. The disk 20 may be located at any suitable place intermediate the closed and open ends of the member 21 and also may be provided with 90 openings, if desired, to provide for the escape of liquid from the interior of the member 21 which may enter or accumulate therein. While in Figs. 1 and 2 I have shown the control member as comprising a 95 disk 20 and a bell shaped member 21 it will be observed, however, that a single transverse substantially flat member 20' may be

used, if desired, with substantially equal effect, such member being connected to the stem 15 and the flange 22 at a suitable distance above the rim 23, as shown in Fig. 3, the 5 arrangement of the parts in either case thus providing an inverted shallow substantially cup-shaped chamber beneath the disk and bounded by it and the flange 22.

The members 20 and 21 or 20' with the 10 stem 15 and valve 19 are of comparatively light weight, may be conveniently made of thin drawn metal and suitably spaced from the walls of the shell 9 to provide a relatively large annular passage therebetween, but with 15 the flange 22 and rim 23 spaced to form a small opening or orifice between the rim 23 and the interior wall of shell 9, as well as to provide an annular orifice between the rim 23 and the inner face of the flange 7.

20 The weight of the movable parts 20 or 20', 21, 15 and 19 and the effective area of the valve 19 are such that the mere pressure of the heating medium in the radiator will not be sufficient to sustain the weight of the 25 movable parts after the valve 19 has closed, the maintaining of the valve 19 in closed condition being effected in a manner herein-after more fully disclosed.

In operation, starting with the system in 30 cold condition and the parts of the vent device in the position shown in Fig. 1, with the lower end of the valve 19 resting upon the bottom of the well 4, upon the admission to the radiator of the heating medium, such as 35 steam, the relatively cold air and vapors in the radiator will flow into the connection 1, well 4, and past the valve 19 into the cup 5, thence through the orifice or space provided between the rim 23, and the flange 7 and then 40 flowing by the rim 23, through the narrow orifice provided therebetween and the wall of the shell 9, into the interior of the shell 9. The flow thence continues upwardly and causes said air and vapors to contact with 45 the concave surface of the portion 11, where a reflex flow is effected, the vapors and air then passing to the central portion of the interior of the shell 9 and finally escaping through the apertures 13 and 18 to the atmosphere. The valve remains in open position during the upward flow of said air and vapors, the colder air and vapors first flowing through the device followed by the 50 warmer air and vapors, the latter being followed by the steam.

As soon as the steam flows into the cup 5 and the shell 9, its contact with the relatively cold walls thereof will cause the steam to condense, flow back and accumulate in the 55 cup 5, the curved form of the portion 11 aiding, by reflecting the steam impinging against the same, to increase the condensing action and to prevent excessive escape of the steam through the perforation 13. As the 60 water of condensation accumulates in the

cup 5, and lower part of the interior of the shell, further flow of steam past the valve 19 causes an agitation or ebullition of the water, which appears to impart a sudden impulse or "kick" upwardly to the disk 20 which 70 moves the valve against its seat, the upper surface of the water substantially simultaneously with the upward movement of the parts and closing of the valve on its seat assuming the form of a concave meniscus and 75 adhering to rim 23 and wall 9 thus sealing the space therebetween, the valve thereafter remaining closed, although the weight of the movable parts is greater than the effective pressure upon the valve 19, the parts then 80 being in the position shown in Fig. 2 of the drawing. From experiments carried out with this type of device it appears that the surface of the water extends across the narrow annular orifice provided between the rim 23 and the inner surface of the shell 9 85 whereby the "skin" or surface tension of the water adhering to the flange 22 and the shell, acts to maintain the movable parts in upper or closed position, the contractile tendency 90 of the surface of the water at said orifice being apparently sufficient to counteract the difference in the weight of the movable parts and the effective pressure or thrust of the steam upon the valve 19 until said water surface be destroyed or broken in a manner 95 hereinafter more fully disclosed.

The above operation is that which occurs under ordinary conditions. If, however, unusual conditions exist, such as the presence 100 of a large quantity of water accumulated in the radiator, it will be apparent that upon the admission of steam into the radiator there will be a tendency to force said water upwardly through the radiator and the vent 105 valve. The rush of water so caused will enter the vent valve through the passage 3, pass into the well 4, and thence through the port of the valve seat 6 into the cup 5 and interior of the shell 9, where the water will 110 accumulate and rise to a sufficient depth or height to lift the movable parts upwardly by floatative force, a sufficient distance to cause a closing of the valve 19 against its seat 6, thereby preventing further flow of the water 115 from the radiator and the consequent escape thereof from the vent valve into the room where the radiator may be located. These conditions are, however, somewhat unusual in practice, as ordinarily there is not sufficient accumulated water in the radiator or in the vent valve to fill the chambers of the vent valve to a sufficient height to cause a closing of the valve 19 prior to the passage of steam therethrough.

Under the more usual conditions encountered in practice, there is but little or no residual water of condensation in or adjacent the vent valve when the steam or other heating medium is admitted to the radiator. 120 125 130

While under normal conditions and after the steam has been admitted and the air and vapors vented as heretofore described, the valve 19 is held to its seat, it is not certain just what are the forces acting to accomplish this result but it would appear from experiments carried out with devices constructed in accordance with the invention, that as the steam enters the water of condensation accumulated in the cup 5 and causes an ebullition or agitation thereof or otherwise acts upon it to close the valve, such steam is condensed with the water and increases the bulk thereof. As can be observed in a suitably constructed device the water has a concave surface which extends to the rim 23 and the shell 9, it is thought that the portion of the surface spanning the rim 23 and the shell 9 is maintained under sufficient surface or skin tension to react against the movable parts to maintain them in upper or closed position as heretofore stated.

After the radiator has been in operation for a time the valve will occasionally open and again close. While the reason for this action is not certain it would appear from the experiments heretofore referred to that the valve 19 is not maintained absolutely or hermetically sealed but that a very small amount of steam constantly enters the cup 5 and collects above the surface of the water, where its pressure in time increases sufficiently to force a bubble or more thereof through the orifices adjacent the rim 23, thus breaking or destroying the surface under tension at the rim orifice, or possibly the heat from the heating medium is transmitted through the bottom of the cup 5 which causes an evaporation of a certain amount of water in the cup 5 whereby the steam thus formed is forced through the orifice beneath the rim 23 and through the narrow orifice provided between the rim 23 and the shell 9, thereby breaking or destroying the water surface under "skin" tension at said orifice. In either event the breaking of said surface permits the movable parts, due to their weight, to move downwardly and open the valve 19, when more steam immediately flows into the cup 5 again causing an ebullition or agitation therein and increasing upon condensation, the bulk of the water, whereby the valve is again closed and maintained closed for a time, as before.

While I have herein described and shown upon the accompanying drawing certain embodiments of my invention, it is to be understood that the latter is not limited to the particular details disclosed but that such other forms are comprehended by said invention as do not depart from the spirit of the invention and the scope of the appended claims.

Having thus described my invention, I

claim and desire to protect by Letters Patent of the United States:

1. A radiator vent valve comprising a shell, a cup connected to the lower end of said shell, means for connecting said cup to a radiator, said cup being provided with a valve controlled opening, a valve therefor, means in said shell and connected to said valve adapted to close said valve upon the accumulation of water of condensation in said cup and to effect an opening of said valve upon destruction of the surface tension of said water of condensation. 75

2. A radiator vent valve comprising a shell having a chamber, a cup connected to said shell and having a chamber therein in communication with the chamber of said shell, means provided with a passage and a valve chamber connecting said cup to a radiator, said cup being provided with a valve-controlled opening between the chamber of said cup and said valve chamber, a valve in said valve chamber for controlling said opening, a movable member having a downwardly depending flange carrying an outwardly directed rim in said shell, and means extending through said opening and connected to said movable member and said valve. 80 90

3. A radiator vent valve comprising means provided with a plurality of aligned chambers, means for connecting one of said chambers with the interior of a radiator, means for closing and opening communication between contiguous chambers operative to move in one direction upon the accumulation of water of condensation in said cup and to move in the other direction upon the destruction of the surface tension of said water. 95 100

4. A radiator vent valve comprising three aligned chambers, a passage connecting the first of said chambers with the interior of a radiator, means for controlling communication between the first and second chambers, a movable member having a downwardly depending flange and an outwardly directed rim for controlling the movement of said means located in the third chamber, and a rod connecting said first and second mentioned controlling means whereby the same 110 115 move in unison.

5. A radiator vent valve comprising three aligned chambers, a passage connecting the first of said chambers with the interior of a radiator, valve controlled opening between the first and second chambers, a valve therefor, movable means in the third chamber comprising a wall provided with a downwardly depending and laterally extending rim proximate to the wall of said third chamber for providing a relatively narrow annular orifice therebetween, means for connecting said valve and said movable means whereby said valve and said movable means move in unison, said valve and said movable 120 125 130

means being operative to close communication between said first and second chambers upon accumulation and agitation of water of condensation in said second and third 5 chambers, and to open said valve upon the destruction of the surface tension of the water of condensation in said third chamber.

6. A radiator vent valve comprising a cup provided with a flange, a shell connected 10 at one end thereof to said flange, a connection from said radiator to said cup, a valve controlled opening provided in the bottom of said cup, a valve therefor, a movable member in said shell above said cup provided with a downwardly depending portion carrying an outwardly extending rim proximate to the wall of said shell and providing a relatively narrow orifice therebetween, and means connected to said movable member 15 20 and said valve.

7. A radiator vent valve comprising a shell, a fluid receiving cup connected to the lower end of said shell, means for connecting said cup to a radiator, and means for 25 controlling communication between said connecting means and said cup, said shell having a wall at the upper end thereof provided with a concave portion adapted to cause reflex flow of fluids flowing upwardly 30 in said shell.

8. A radiator vent valve comprising a shell, a fluid receiving cup connected to the lower end of said shell, means for connecting said cup to a radiator, and a valve stem 35 carrying a valve for controlling communication between said connecting means and said cup, said shell having a wall at the upper end thereof provided with a concave portion adapted to cause reflex flow of fluids upwardly 40 in said shell and provided with an opening forming a guide for said valve stem and with a vent opening adjacent said concave portion for the escape of air and vapors.

45 9. A radiator vent valve comprising a shell, a liquid receiving cup connected to the lower end of said shell, means for connecting said cup to a radiator, a valve stem carrying a valve for controlling communication 50 between said connecting means and said cup, said shell having a wall at its upper end provided with a concave portion adapted to cause reflex flow of fluids flowing upwardly 55 in said shell and having a vent opening adjacent said concave portion for the escape of air and vapors and a guide opening for said stem, and a cap connected to the upper end of said shell and provided with a vent aperture.

60 10. A radiator vent valve comprising a shell, a liquid receiving cup connected to the lower end of said shell, means for connecting said cup to a radiator, and means for controlling communication between said 65 connecting means and said cup.

11. A radiator vent valve comprising a cup, means for connecting said cup to a radiator, a casing above the cup and connected thereto, a valve seat in the bottom of said cup, a valve, a valve stem, and a horizontally positioned member located in said casing movable with said valve and said valve stem and having an annular depending flange and an annular outwardly extending rim adjacent the bottom of said flange, the 70 edge of said rim lying adjacent but spaced from said casing.

12. A radiator vent valve comprising a casing, a flanged cup below said casing, a well below said cup, means for connecting 80 said well to a radiator, a valve seat in the bottom of said cup, a valve cooperative with said seat, a valve stem movable with said valve, and a horizontally positioned member in said casing above said cup movable with 85 said stem and having an annular depending flange and an outwardly projecting rim surrounding said flange, the edge of said rim being adjacent but out of contact with said casing, and said valve being adapted to rest 90 on the bottom of said well to maintain said rim in vertically spaced relation with the flange of said cup.

13. A radiator vent valve comprising a casing, a flanged cup beneath said casing, 95 a well beneath said cup, means for connecting said well with a radiator, a valve stem passing through said cup and a substantially flat member above said cup and in said casing 100 movable with said valve stem and having an annular depending flange and an outwardly extending rim adjacent the bottom of said flange, said valve being adapted to rest on the bottom of said well to prevent the contact of said flange with the flange of said cup.

14. A radiator vent valve comprising a casing, a cup below the casing, a valve seat in said cup, a valve stem extending through said cup and into said casing, a valve carried by said stem adapted to close onto said seat, 110 and a movable member in said casing having a depending flange and an outwardly directed rim with its edge adjacent but spaced from the interior of said casing, and means for supporting said valve when out of engagement with said seat so as to maintain said rim out of engagement with said cup.

15. A radiator vent valve comprising a casing, a cup below the casing, a valve seat in the base of the cup, a valve stem extending through the cup and into the casing, a valve carried by the stem and adapted to close onto said seat, and a member in the casing and movable with said valve stem comprising a transversely extending portion, a 120 downwardly depending flange therebelow and an outwardly directed rim carried by the flange.

16. A radiator vent valve comprising a cup, means for connecting the cup to a ra- 130

diator, a casing above the cup, a valve operative to control admission of fluid to the cup, and a horizontally positioned member located in the casing movable with the valve and having a depending flange adjacent but spaced from the interior of said casing.

17. A radiator vent valve comprising a casing, means for connecting said casing to a radiator, a valve operative to control the admission of fluid to the casing from the radiator, and a member located in said casing movable with said valve and having an annular depending flange lying adjacent but spaced from the interior of the casing.

18. A radiator vent valve comprising a casing, a cup below the casing, a valve seat in the base of the cup, a valve cooperative with said seat, and a member in the casing movable with said valve comprising a transversely extending portion and a depending rim bounding an inverted cup-shaped chamber extending over said cup.

19. The method of effecting the closure of a radiator vent valve having a body portion and a relatively movable valve member controlling the flow of fluid therethrough, which consists in effecting condensation of steam within said body to accumulate a quantity of water of condensation therein and agitating said accumulated water by the introduction of additional steam from the radiator to effect the movement of said valve member against its seat.

20. The method of operating a radiator vent valve having a body portion and a relatively movable valve member therein cooperative with a valve seat, which consists in causing steam from said radiator valve to flow through said body portion and to condense therein and continuing the flow of steam through the accumulated water of condensation to effect an agitation thereof to move said valve member into contact with its seat.

21. The method of maintaining a movable valve member of a radiator valve in position to prevent a flow of fluid through the valve, which consists in effecting a partial support of said valve through the surface tension of water of condensation accumulated in the body of the valve.

22. The method of operating a radiator valve comprising a body and a relatively movable valve member therein in such manner as to prevent escape of steam from the valve, which consists in effecting a movement of said valve member against its seat through the agitation of water of condensation in said body and thereafter maintaining said valve member on its seat by effecting the partial support thereof through the medium of the surface tension of said water.

In witness whereof, I have hereunto set my hand this 10th day of June, 1920.

ANDREW HELDRICH.
